ROELOF VERMEULEN, OF EINDHOVEN, NETHERLANDS, ASSIGNOR TO RADIO CORPORATION OF AMERICA, A CORPORATION OF DELAWARE

MAGNET SYSTEM FOR CONVERTING ELECTRIC OSCILLATIONS INTO ACOUSTIC ONES OR CONVERSELY

Application filed August 10, 1928, Serial No. 298,827, and in the Netherlands September 24, 1927.

This invention relates to a magnet system for converting electric oscillations into acoustic oscillations and conversely. More particularly it relates to a magnet system provided with a ferromagnetic armature which is normally balanced in a permanent magnetic field and which is adapted to move from that balanced position when speech modulated currents are passed thru windings associated with said system.

The invention has for its object to provide a magnet system of the kind referred to which has a very simple construction and which can be cheaply and easily made. Another object is to provide a path of minimum resistance for the alternating flux developed by the speech modulated currents.

The magnet system according to the invention is so constructed that the permanent flux is branched off from one pole of a permanent magnet through the armature to pole-surfaces of a U- or V-shaped pole piece attached to the other pole of the permanent magnet. The active faces of the U shaped pole piece are normal to the direction of movement of the armature, and said pole piece constitutes with the armature, a closed circuit for the alternating flux produced by the speech modulated current in flowing thru coils that are mounted on the U-shaped pole piece. When both the U-shaped pole piece and the armature are laminated, this part will be similar to a transformer core and consequently will constitute an ideal path for the induced alternating current. The active pole faces of the U-shaped pole piece being normal to the direction of movement of the armature, air gaps will be produced between the ends 40 of the armature and the active faces of the pole piece. Owing to this arrangement a variation in the magnetic field will exercise a greater force on the armature than in the case where the air gap is parallel to the direction of movement of the armature.

In one embodiment of the invention the U- or V-shaped pole piece has arranged opposite it another pole piece to which the armature is secured by means of unilaterally clamped 50 springs. The two pole-pieces may be located

essentially in one plane and for convenience can be mounted on a copper plate which is provided with notches adapted to receive the limbs of the magnet. The construction of the magnet system is very simple as it is built up of but four parts. In the first place the horse-shoe magnet which in the majority of cases is permanent but may be provided with direct current windings, secondly the U-shaped pole piece with two coils that are slipped on the limbs of the U, in the third place the other pole piece to which the armature is secured by means of springs, in the fourth place the copper plate on which the two pole pieces can be mounted by very simple means and which owing to its notches can be very simply slipped on the horse-shoe magnet.

The invention will be more clearly understood by reference to the accompanying drawing in which an embodiment of the invention is illustrated. In the said drawing:

Figure 1 is a side view of a magnet system according to the invention.

Figure 2 is a plan of the magnet system shown in Figure 1.

Figure 3 is a bottom view of the copper plate on which the two pole pieces are mounted.

Figure 4 is a detail view of the U-shaped pole piece with the speech current coils mounted thereon.

Figure 5 is a detail view of the other pole piece with the armature secured to it.

Figure 6 shows diagrammatically the progress of the permanent and the alternating flux.

Before entering into the details of the magnet system the principle on which it is based will be briefly explained with reference to Figure 6. In this Figure, 1 designates a permanent magnet. This horse-shoe magnet has secured to one pole a pole piece 2 and to the other pole a U-shaped pole piece 3. Speech modulated current coils 9 and 10 are mounted on the limbs of the U-shaped pole piece 3. The ferromagnetic armature 5 is secured to the pole piece 2 by means of springs 12 and 13.

Assuming the case that the pole piece 2 is secured to the north pole the permanent flux

will proceed as indicated by the light line, through this pole piece to the armature and there be branched off to the two limbs of the U-shaped pole piece 3, the pole faces of which 5 are normal to the direction of movement of the armature. The pole faces are hereinafter understood to mean those parts of the pole piece that together with the armature limit the intermediate air gap. As before stated 10 the limbs of the U-shaped pole piece are provided with speech modulated current coils and if the latter are wound in a correct direction an alternating flux will be produced which makes its way through the armature 15 and the U-shaped pole piece as indicated by dotted lines. From this it follows that this alternating flux traverses a closed circuit constituted by pole piece 3 and armature 5. When these two parts are laminated the resistance 20 for the alternating flux becomes extremely low so that the flux reaches a high value.

In Figure 1 a side view of the magnet system is shown. The U-shaped magnet 1 has mounted on it a copper plate 7 which serves 25 as a mounting plate for pole piece 2 and U-shaped pole piece 3. In Figures 2 and 3 two views of this copper plate with pole pieces mounted on it are shown. As shown in Figure 2 pole piece 3 is secured to the copper 30 plate 7 by means of clamps 8 and that two coils 9 and 10 are mounted on the limbs of the pole piece. Pole piece 2 is fastened to the copper plate 7 by means of screws 11. This pole piece has mounted on its springs 12 and 35 13 which serve as carriers for the armature 5. A stud 14 which communicates with an oscillation member, for example a cone, is fastened to the armature 5.

Figure 3 shows a bottom view of the copper 40 plate. The notches in which the limbs of the horse-shoe magnet are fitted and by means of which the copper plate 7 can be secured to the limbs of the horse-shoe magnet, are indicated at 15 and 16.

Figures 4 and 5 show in detail the pole 45 pieces 3 and 2. As shown in Figure 5, armature 5 is secured to the pole piece 2 by means of springs 12 and 13. These springs are unilaterally clamped by means of screws and 50 are secured to the pole piece 2. Pole piece 3 and armature 5 are laminated so that the alternating flux meets with a low resistance.

Various other modifications can be made 55 without departing from the spirit of my invention and I do not intend to be limited by the exact structure disclosed but only by the scope of the appended claims.

I claim:

1. In combination a permanent magnet, a 60 U-shaped pole piece fastened to one of the poles of said magnet, an armature positioned with one end adjacent one of the limbs of said U-shaped pole piece and with its other end adjacent the other limb of said U-shaped 65 pole piece, a single limb pole piece fastened

to the other pole of said magnet, said pole piece being positioned with its single limb adjacent the intermediate part of said armature, an operating member connected to said armature, a pair of coils mounted on the 70 limbs of said pole piece, and means supporting said armature for movement along its longitudinal axis.

2. In combination means for forming a permanent field of magnetic flux, a pair of 75 pole pieces for said means, one of said pole pieces being branched, an armature positioned between the limbs of the branched pole piece with one end adjacent one limb and the other end adjacent the other limb, 80 a pair of modulated speech current coils mounted on the limbs of said branched pole piece for superposing an alternating field of magnetic flux on said permanent field of magnetic flux, and means for supporting said 85 armature from the other pole piece for movement substantially along its longitudinal axis.

3. In combination a permanent magnet, a 90 U-shaped pole piece fastened to one pole of said permanent magnet, a second pole piece fastened to the other pole of said permanent magnet and positioned to form two air gaps between said second pole piece and the limbs of said U-shaped pole piece, an armature supported from said second pole piece and positioned to move between the limbs of said U-shaped pole piece and a pair of modulated speech current windings mounted on the 95 limbs of said U-shaped pole piece. 100

4. In combination a permanent magnet, a U-shaped pole piece fastened to one of the poles of said magnet, an armature positioned with one end adjacent one of the limbs of said U-shaped pole piece and with its other 105 end adjacent the other limb of said U-shaped pole piece, a driving rod connected to said armature, a pair of supporting springs secured to the ends of said armature, windings surrounding the limbs of said U-shaped pole 110 piece whereby said armature lies within its magnetic field, and a pole piece fastened to the other pole of said magnet and positioned adjacent the side of said armature, said last mentioned pole piece and said armature being arranged so that the air gap between 115 said pole piece and the side of said armature is not varied by vibration of the armature.

5. In combination means for producing a permanent magnetic field, a U-shaped pole 120 piece fastened to said means, a solid pole piece fastened to said means, an armature positioned between the limbs of said U-shaped pole piece and adapted to move substantially along its longitudinal axis, windings surrounding the limbs of said U-shaped pole piece, and a pair of springs secured to the ends of said armature and to said solid pole piece. 125

6. A magnet system for the interconver- 130

- sion of electric oscillations and sound waves comprising means including a U-shaped pole piece and a second pole piece having one limb for forming a permanent magnetic field, said
- 5 U-shaped pole piece being arranged opposite said second pole piece, a ferromagnetic armature arranged in said magnetic field and adapted to move substantially along its longitudinal axis, said armature being positioned with one end adjacent one of the pole surfaces of said U-shaped pole piece and with the other end adjacent the other pole surface of said U-shaped pole piece whereby the permanent flux is branched off from said
- 10 second pole piece through the armature to the pole surfaces of said U-shaped pole piece which are normal to the direction of movement of the armature, said U-shaped pole piece constituting with said armature a closed circuit for alternating flux, coils for the speech modulated current mounted on the U-shaped pole piece to produce said alternating flux, and springs clamped to said second pole piece and secured to the ends of
- 15 said armature for supporting said armature.
7. A magnet system according to claim 6, characterized in that the two pole pieces are located essentially in one plane and are mounted on a copper plate which is provided
- 20 with notches adapted to receive the limbs of the magnet.
